US0D1083902S

(12) **United States Design Patent** (10) **Patent No.:** **US D1,083,902 S**
(45) **Date of Patent:** **** Jul. 15, 2025**

(54) **MAGNETIC SUPPORT**

(71) Applicant: **Weiyu (Shenzhen) Technology Co., Ltd.**, Shenzhen (CN)

(72) Inventors: **Yuchen Qiu**, Guangdong (CN); **Yaohua Xie**, Guangdong (CN)

(**) Term: **15 Years**

(21) Appl. No.: **35/522,184**

(22) Filed: **Jul. 18, 2024**

(80) **Hague Agreement Data**

Int. Filing Date: **Jul. 18, 2024**

Int. Reg. No.: **DM/239586**

Int. Reg. Date: **Jul. 18, 2024**

Int. Reg. Pub. Date: **Sep. 6, 2024**

Primary Examiner — Rebekah A Caruso

(57) **CLAIM**

The ornamental design for a magnetic support as shown and described.

DESCRIPTION

1. Magnetic support

1.1 : Front

1.2 : Back

1.3 : Left

1.4 : Right

1.5 : Top

1.6 : Bottom

1.7 : Perspective

1.8 : Perspective

1.9 : Perspective

1.1 is a front view of a magnetic support showing our new design; 1.2 is a rear view thereof; 1.3 is a left view thereof; 1.4 is a right view thereof; 1.5 is a top view thereof; 1.6 is a bottom view thereof; 1.7 is a front, top and right side perspective view thereof; 1.8 is a front, bottom and right side perspective view thereof; and 1.9 is a rear, top and left side perspective view thereof.

1 Claim, 9 Drawing Sheets
